[57] CLAIM

The ornamental design for a mechanical game, substantially as shown and described.

DESCRIPTION

FIG. 1 is a side elevational view of a mechanical game showing my new design; the side opposite being a mirror image;

FIG. 2 is an end elevational view thereof, the end opposite being a mirror image;

FIG. 3 is a top plan view thereof; and

FIG. 4 is a bottom plan view thereof.

Fig. 3

Fig. 4
